CRYSTAL OSCILLATOR CIRCUIT

Reginald L. Downey, Scotia, N. Y., assignor to
General Electric Company, a corporation of
New York

Application February 13, 1943, Serial No. 475,732

8 Claims. (Cl. 250—36)

My invention relates to oscillator circuits employing piezoelectric devices.

In oscillator circuits employing piezoelectric devices and especially in circuits employing an electron discharge device having a tuned anode circuit and having a crystal connected between the control electrode and cathode, it has been necessary to tune the anode circuit appreciably on the high frequency side of the operating frequency of the piezoelectric device in order to obtain proper conditions for quick and stable starting of the oscillator. After oscillations have been started, the anode tuned circuit has been retuned for higher output. In such a case, however, if oscillations are halted for any reasons whatsoever, oscillations may not start again unless the circuit is again tuned to the high frequency side of the operating frequency. For high frequency crystals, such as those having a natural frequency in the range of 1,000 to 10,000 kilocycles, the optimum operation of the oscillator is usually obtained when the anode oscillatory circuit is tuned to about 102 per cent to 110 per cent of the crystal frequency, depending on the output, frequency stability and tube current conditions. For low frequency crystals, as for example, in the range of 50 to 500 kilocycles, it is often necessary to tune the anode oscillatory circuit as much as 125 to 150 per cent of the crystal frequency in order to obtain proper starting of the crystal.

It is, therefore, an object of my invention to provide a new and improved oscillator circuit which does not require mechanical adjustment to provide optimum starting and operating conditions.

It is another object of my invention to provide a new and improved oscillator circuit employing piezoelectric devices which provides positive starting of oscillations even though the anode tuned circuit is tuned to a frequency providing optimum operating conditions.

In accordance with my invention there is provided in combination with a piezoelectric or crystal oscillator having a tuned anode circuit, automatic means dependent upon the oscillator output for tuning the circuit between resonance at a frequency at which the crystal oscillates readily and at another frequency at which the desired output is obtained depending upon whether the oscillator is in non-oscillating or oscillating condition. In other words, the anode oscillatory circuit is chosen to be resonant at a frequency different from and preferably higher than the frequency of the crystal and also higher than the frequency at which optimum operation is had

after starting is effected but at which frequency the generation of oscillations readily starts. Means is also provided which is responsive to the starting of oscillations for automatically tuning the oscillatory circuit to a resonant frequency which more closely approaches the frequency at which optimum operation is had. Thus in the absence of control electrode bias the anode circuit tuning is increased progressively farther on the high frequency side toward an optimum starting condition. This means may comprise a reactance device arranged to tune the anode circuit of a crystal oscillator. The reactance device is controlled from the grid current of the crystal oscillator in such a manner that anode tank circuit conditions are optimum for starting when the crystal is not oscillating and optimum to produce maximum output voltage when the crystal is oscillating.

20 The features of my invention which I believe to be novel are set forth with particularity in the appended claims. My invention itself, both as to its organization and manner of operation, together with further objects and advantages thereof may best be understood by reference to the following description taken in connection with the accompanying drawing in which Fig. 1 is a schematic diagram of an oscillator circuit embodying the principles of my invention, and Figs. 2 and 3 illustrate operating characteristics of the circuit shown in Fig. 1.

35 In Fig. 1 there is shown an electron discharge oscillator circuit 10 comprising an electron discharge device 11 having an anode 12, a control electrode 13 and a cathode 14 and having a crystal connected between grid 13 and cathode 14 and a tuned circuit connected between the anode 12 and the cathode 14. The oscillator control electrode is biased by means of resistors 18 and 20. A tuned anode circuit 15 comprising an oscillatory circuit including an inductance 16 and a variable capacitor 17 is connected between the anode 12 and the cathode 14 through a source of potential 40 and ground. Oscillatory circuit 15 is completed from the anode 12 to the cathode 14 for radio frequency currents by means of a suitable bypass condenser 21. Radio frequency in the grid circuit is bypassed around the resistor 18 by a suitable condenser 22. The cathode 14 is grounded.

40 45 50 55 In Fig. 2 there are illustrated typical characteristics of the oscillator circuit shown in Fig. 1. In Fig. 2a, variations of anode current of the electron discharge device 11, plotted as ordinates, are plotted against frequency as abscissa. As the resonant frequency of the oscillatory circuit 15 is

decreased from a maximum, as by varying the variable capacitor 17, oscillations begin at point *a* and the anode current follows the solid line to the point *b* where oscillations cease. The anode current rapidly rises to *c* where the current remains constant at lower frequencies as indicated by the line *c*—*d*. If the condenser is then tuned from the low frequency end toward the high frequency end, oscillations will not begin again until the point *e* is reached, at which point the anode current will suddenly drop to *f* on the original curve. If the tuning is continued in the high frequency direction, the anode current will follow the curve toward *a*. If, however, the tuning is reversed so that the condenser is tuned in the direction of lower frequency, the anode current goes back along the curve toward *b*. The area defined by the letters *b*, *c*, *e*, *f*, is a region of instability. In this range of frequencies, the crystal oscillator will not begin to oscillate if the resonant frequency of the tuned circuit is lower than the frequency represented by the letter *f* on the curve of 2a although oscillations continue, if once started. Therefore, if it is desired to assure certain starting, the oscillatory circuit must be tunable to a point between *a* and *f* on the anode current characteristic. Starting is progressively better as the frequency is increased so that the optimum starting point is well out toward the high frequency end of the curve, as at the point *g*, for example.

On the other hand, it is desired to operate the oscillator circuit at a frequency at which maximum output is obtained. In Fig. 2c there is illustrated the variation in oscillator output, plotted as ordinates, against frequency, plotted as abscissa. It is to be noted that the frequency is plotted on the same scale in each of Figs. 2a and 2c, so that direct comparison can be made between these figures. Comparison of Figs. 2a and 2c shows that while starting conditions are optimum at a point such as *g* in Fig. 2a, at that frequency the output is very low. For maximum output it will be seen that a frequency corresponding to the point *h* is desirable. It is to be noted that this point is in the unstable zone where starting is uncertain.

Means has been provided for automatically shifting the tuning of the oscillatory circuit between frequencies at which optimum starting conditions prevail and at which optimum operating conditions are had.

Connected across the anode tuned circuit 15 is a form of inductance type reactance tube circuit including a phase shifting circuit comprising the series connected inductance 25 and the resistance 26. There is also shown a blocking capacitor 27 in the series circuit including inductance 27 having a capacity such that it has low impedance to the oscillations produced. Across the phase shifting circuit there is disposed an electron discharge device 30 preferably of the pentode type comprising an anode 31, a cathode 32, control electrodes 33, 34 and 35. The anode 31 is connected to the upper end of the inductance 25, the control electrode 33 is connected to a point between the capacitor 27 and the resistor 26, the electrode 34 is connected to the positive terminal of a suitable source of potential 36, the electrode 35 is connected to the cathode and the cathode 32 is connected to ground through the biasing resistor 37 shunted by the capacitor 38. The lower end of the resistor 26 is connected to ground for alternating currents by means of a suitable condenser 41.

The reactance of the winding 25 and the resistance of the resistor 26 are chosen so that the radio frequency voltage on the electrode 33 is approximately 90° out of phase with the output voltage of the tuned circuit 15. Under such conditions, the discharge device 30 draws current from the oscillatory circuit which is 90° lagging, thereby giving the effect of an inductance of approximate value

$$L_0 = \frac{L}{Rg_m}$$

where L_0 is the effective inductance of the reactance circuit, L is the inductance of the coil 25, R is the resistance of the resistor 26 and g_m is the mutual conductance of the electron discharge device 30, i. e., the rate of change of plate current with respect to changes in control electrode voltage.

With the circuit as shown in Fig. 1, if oscillations cease, as when the transmission period for the transmitter with which the oscillator is associated is ended, the oscillator output ceases, resulting in minimum bias of the control electrode 33 of the electron discharge device 30. Therefore, the g_m of the discharge device increases and L_0 is decreased. Therefore, the effective reactance of the tuned oscillatory circuit 15 is decreased and the resonant frequency of the tuned circuit is increased under the assumed conditions. The variation of resonant frequency of the tuned circuit with the voltage on control electrode 33 is shown in Fig. 3 in which frequency is plotted along the abscissa (to the same scale as in Fig. 2) and the control electrode voltage is plotted along the ordinates. Accordingly, the oscillator is automatically tuned to a frequency such as represented by the point *g* in Figs. 2 and 3.

After oscillations start, as when the oscillator is again switched on, the reverse action takes place. The effective inductance is increased so that the reactance of the tuned circuit is decreased and accordingly the resonant frequency of the anode circuit is changed to correspond with the point *h*, for example. In other words, the current in discharge device 30 is phased to simulate a reactance of sign and magnitude to effect the desired operation.

The operating and starting points for the oscillator circuit depend upon the bias of the electron discharge device 30 including the resistances 18 and 37. In order to provide control and enable the operator to select the operating and starting frequencies, one of these resistances is made variable. Accordingly, the resistor 18 is of the potentiometer type and is connected between the resistor 20 and ground. The resistor 37 is connected between the cathode 32 and ground and preferably is selected to provide an optimum fixed bias for the tube 30. Resistor 18 should be adjusted to provide the desired output because the range of frequencies for maximum output is rather narrow and critical as indicated by Fig. 2c whereas the range of reasonably good starting conditions is relatively wide as seen in Fig. 2a.

In Fig. 2b there is plotted control electrode current for the tube 11, as ordinates, against frequency of the tuned anode circuit 15. Maximum current occurs near the operating frequency of the crystal 19.

The inductance values of the windings 16 and 25 are made as nearly equal as practicable but large enough to prevent undue loading of the output circuit by the resistance 26. Use of the resistor 37 and condenser 38 in the cathode cir-

cuit of the device 30 stabilizes operation and prevents excessive current being drawn by the discharge device 39. The capacitor 41 not only bypasses the radio frequency current to ground but may also be proportioned to effect a time delay in the operation of the circuit if such is desired.

Tubes of relatively high g_m are necessary for the reactance tube or electron discharge device 30. It has been found that four type 1852 tubes connected in parallel work satisfactorily and with such an arrangement it was possible to operate a crystal ground to oscillate at 100 kilocycles at the point of maximum grid current and even on the low frequency side of this point at approximately maximum output and still achieve instantaneous starting.

A capacity-resistance type phase splitting circuit may be employed, if desired, instead of the inductance-resistance type circuit.

While I have shown and described a particular embodiment of my invention, it will be obvious to those skilled in the art that changes and modifications may be made without departing from my invention in its broader aspects, and I, therefore, aim in the appended claims to cover all such changes and modifications as fall within the true spirit and scope of my invention.

What I claim as new and desire to secure by Letters Patent of the United States is:

1. The combination, in a crystal oscillator, of an electron discharge device having an anode, a cathode, and a control electrode, a piezoelectric crystal connected between said control electrode and cathode, an oscillatory circuit connected between said anode and cathode, said oscillatory circuit being resonant at a frequency higher than the frequency of said crystal and higher than the frequency at which optimum operation is had after starting is effected but at which frequency the generation of oscillations readily starts, and means responsive to oscillations in said oscillatory circuit for lowering the resonant frequency of said circuit to a frequency substantially more closely approaching said frequency at which optimum operation is had.

2. The combination, in a crystal oscillator, of an electron discharge device having an anode, a cathode, and a control electrode, a crystal connected between said control electrode and cathode, an oscillatory circuit connected between said anode and said cathode, said oscillatory circuit being tuned to a frequency at which the generation of oscillations under the control of said crystal readily starts but different from that at which optimum operation of said oscillator is had after the generation of oscillations starts, and means responsive to the generated oscillations to maintain said circuit tuned to a frequency substantially more closely approximating said frequency at which optimum operation is had and upon cessation of oscillations to retune said circuit to said frequency at which oscillations more readily start, whereby both ready starting and optimum operation thereafter is had.

3. The combination, in a crystal oscillator, of an electron discharge device having an anode, a cathode, and a control electrode, a crystal connected between said control electrode and cathode, an oscillatory circuit connected between said anode and said cathode, said oscillatory circuit being tuned to a frequency at which the generation of oscillations under the control of said crystal readily starts but different from that at which optimum operation of said oscillator is had after the generation of oscillations starts, and means

responsive to the generated oscillations to maintain said circuit tuned to a frequency substantially more closely approximating said frequency at which optimum operation is had, said means comprising a second electron discharge device connected across said oscillatory circuit, and means to phase the current in said second discharge device to simulate a reactance of sign and magnitude to maintain said oscillatory circuit tuned to said last mentioned frequency.

4. In combination, an oscillator of the type having an electron discharge device having an anode, a cathode and a control electrode, a piezoelectric device connected between the control electrode and the cathode, and an oscillatory circuit connected between the anode and cathode, and means dependent upon the output of said oscillator for automatically tuning said circuit between resonance at a frequency at which said device readily begins to oscillate and at another frequency at which a desired output is obtained according to whether said piezoelectric device is in non-oscillating or oscillating condition, respectively.

5. In combination, an oscillator of the type having an electron discharge device having an anode, a cathode and a control electrode, a piezoelectric device connected between the control electrode and the cathode, and an oscillatory circuit connected between the anode and cathode, and means in shunt to said oscillatory circuit for varying the effective reactance of said circuit in accordance with the output of said oscillator thereby to vary the resonant frequency thereof between frequencies at which said device readily begins to oscillate and at which a desired output is obtained, according to whether said piezoelectric device is in non-oscillating or oscillating condition.

6. In combination, an oscillator of the type having an electron discharge device having an anode, a cathode and a control electrode, a piezoelectric device connected between the control electrode and the cathode, and an oscillatory circuit connected between the anode and cathode, and a phase shifting circuit in shunt with said oscillatory circuit and operative in accordance with the output of said oscillator to tune said oscillatory circuit between resonance at a frequency at which said device readily begins to oscillate and at another frequency at which a desired output is obtained according to whether said piezoelectric device is in a non-oscillating or an oscillating condition, respectively.

7. In combination, an oscillator of the type having an electron discharge device having an anode, a cathode and a control electrode, a piezoelectric device connected between the control electrode and the cathode, and an oscillatory circuit connected between the anode and cathode, and means dependent upon the output of said oscillator for automatically tuning said circuit between resonance at a frequency at which said device readily begins to oscillate and at another frequency at which a desired output is obtained according to whether said piezoelectric device is in non-oscillating or oscillating condition, respectively, and means for adjusting the point of operation for the desired output of said oscillator.

8. In combination, an oscillator of the type having an electron discharge device including an anode, a cathode and a control electrode, a piezoelectric device connected between the control electrode and the cathode, resistance means in shunt with said piezoelectric device for pro-

viding bias for the control electrode of said discharge device, an oscillatory circuit connected between the anode and cathode of said electron discharge device, and means dependent upon the output of said oscillator for automatically tuning said circuit between resonance at a frequency at which said device will readily begin to oscil-

late and another frequency at which substantially maximum output is obtained according to whether said piezoelectric device is in a non-oscillating or oscillating condition, and adjustable means operable in conjunction with said resistance means to vary said other frequency.

REGINALD L. DOWNEY.
